(57) **CLAIM**

The ornamental design for a miniature landscape lamp, as shown and described.

DESCRIPTION

FIG. 1 is an isometric view of the miniature landscape lamp in a closed configuration, embodying the claimed design; FIG. 2 is an isometric view of the miniature landscape lamp in a directional configuration, embodying the claimed design;

FIG. 3 is an isometric view of the miniature landscape lamp in a closed configuration, embodying the claimed design;

FIG. 4 is a front elevation view thereof;

FIG. 5 is a rear elevation view thereof;

FIG. 6 is a right elevation view thereof;

FIG. 7 is a left elevation view thereof;

FIG. 8 is a top plan view thereof; and,

FIG. 9 is a bottom plan view thereof.

The portions shown in broken lines are not part of the claimed design but show the environment in which the design is associated.

1 Claim, 9 Drawing Sheets
